J. WILHELM ET AL

MECHANICAL TOY

Filed Aug. 25, 1920

INVENTORS:

Charles A. Kays & Joseph Wilhelm

UNITED STATES PATENT OFFICE.

JOSEPH WILHELM AND CHARLES A. KAYS, OF MCKEES ROCKS, PENNSYLVANIA.

MECHANICAL TOY.

Application filed August 25, 1920. Serial No. 406,020.

To all whom it may concern:

Be it known that JOSEPH WILHELM and CHARLES A. KAYS, citizens of the United States, residing at McKees Rocks, in the county of Allegheny and State of Pennsylvania, have invented certain new and useful Improvements in Mechanical Toys, of which the following is a specification.

This invention relates to mechanical toys and more particularly to automatic toys operated by the force of gravity.

One of the main objects of this invention is to provide a toy of simple construction and cheap manufacture, devoid of ropes, pulleys or other mechanical elements which are easily put out of working order. Another object is to produce a toy in which the weight of marbles is used to produce the necessary operating power. A further object is to provide a toy having simultaneously a horizontal rotary motion and a vertical swinging motion. Still a further object is to provide a toy that can be easily taken apart for shipment and storage in reduced size containers.

In the drawings which represent the preferred construction of the invention, and which form part of this specification—

Fig. 1 is a perspective view showing the complete toy assembled and ready for operation.

Fig. 2 is a detail view showing the side elevation of the marble bucket, positioned at the forward end of the rocker-beam.

Fig. 3 is a plan view corresponding to Fig. 2.

Fig. 4 is a cross sectional view showing the marble gate in position for arresting the downward rolling motion of the marbles.

Fig. 5 is also a cross sectional view showing the marble gate in position for releasing the first marble and stopping the other marbles in the rear.

Referring more in detail to the drawings, the preferred construction of this toy consists of an open marble trough 1 supported by the four legs 2. The trough is suitably inclined to enable the marbles to roll by their own force of gravity into the narrowed forward or lower part 3, hereafter to be called the runway of the trough. Adjacent to the end of the runway a hole 4 is cut in the bottom 5 of the trough, sufficiently large to allow a marble to fall through. The marbles 6 are prevented from running out through hole 4 by a special

trigger operated gate 7 which consists of a marble-gate 8 made of a suitably bent strip of sheet metal cut to operate within the runway and secured to a shaft 9 rockably mounted in two bearings 10 and 10^a, provided in supports 11 and 12 outwardly secured on each side of the runway. The inner end of the shaft 9 is extended a suitable amount beyond the support 11 and is provided with a finger 13 bent downwardly and at right angle to the shaft. This finger engages into an oblong hole 14 provided in the horizontal arm 15 of the trigger lever 16, rockable at 17 on a rivet 17^a supported by the inner wall of the runway. The lower end 16^a is made of sufficient length and weight to keep the trigger lever normally in a vertical position by the force of gravity.

The moving part proper of the toy consists of a vertical post 18, preferably of channel shaped cross section owing to the rigidity afforded thereby, pivotally mounted at its lower and upper end by the pins 19 and 20 secured to the post and working in the lower bearing 21 and in the upper bearing 22 provided in the bracket 23 the legs 24 and 25 of which are suitably secured to the trough to insure proper alignment of the post. A rocker beam 26 is rockably mounted on pin 27 supported by the flanges of the post intermediate its supports and is provided at its forward end with the bucket 28, preferably made out of a single piece of sheet metal, for receiving a marble as it falls through the hole 4. Both sides 29 and 30 of this bucket are secured to the legs of the beam 26, the rear end being closed by the wall 31 to prevent the marble from rolling backward when the beam occupies the position shown in Fig. 1. A discharge spout 32 is provided at the forward end of the bucket and is suitably inclined so as to hold the marble in the bucket during its downward and rotating motion, while also enabling the marble to roll out of the bucket when the latter has reached its lowermost position.

The rear end of the balancing beam is provided with a counterweight 33, so proportioned that the rear end will outweigh the forward end of the beam when the bucket is empty, and that this condition will be reversed as soon as the bucket has received a marble. Both sides of the rocker beam are stiffened by the flanges 34 pro-

vided on the outside of the beam and also by the tie plate 35 placed between both legs of the beam and secured thereto.

Adjacent to the lower end of the post, a horizontal shaft 36 is rotatively mounted in both flanges of the post and is provided at the forward end with a small rack gear 37 secured thereto and which is acted upon by the rack bar 38, the lower end of which is provided with teeth 39 meshing with the gear and the upper end rockably mounted on pin 40 secured to the rocker beam at a point located behind the fulcrum of the beam. Permanent and correct engagement of the rack and gear is obtained by means of the guide sleeves 41 provided in plate 42 which is rockably mounted on the shaft, and inserted between the gear and the post, so as to follow the oscillating motion described by the rackbar.

On the rear end of shaft 36 is secured a crown gear 43, preferably made of stamped metal and meshing with a stationary crown gear 44, of sufficient depth to clear the rack when at its lowest position, provided with a bottom 45 in the center of which is formed an inwardly projecting depression 46 provided with the hole 21, forming the lower bearing and guide for the pin 19 of the post.

The shaft is shown in Fig. 1 as being provided with a crank 50, it being our intention to provide the toy with an articulated figure of a man not shown standing upon a platform not shown and holding the crank in his hands, thus conveying the idea as though he were operating the toy instead of the marbles.

The stationary crown gear is securely mounted on a base 47, preferably made of sheet metal, which forms also the base for the four legs 2 which are held in position by inserting their bent feet 2^a into the sleeves 48 stamped directly in the base. The legs are furthermore stiffened by the braces 49 secured and suitably positioned on the legs.

Assuming that the trough be provided with marbles and that the toy be not working, the marbles will be prevented from rolling out through the hole 4, in the runway, by the gate mechanism which will occupy the position shown in Fig. 4. Owing to the force of gravity due to its weight, the trigger lever will be vertical and thereby cause the marble gate to take a practically horizontal position, its curved forward end preventing the first marble from passing under it.

When it is desired to operate the toy, a slight push is given the bucket end of the rocker beam against the trigger, thereby forcing the lower end of the latter backward and causing the finger 13 of the gate shaft, and the gate proper, to describe a clock-wise movement and take the position shown in Fig. 5. The forward end of the gate will

be raised a sufficient amount to clear the marble and allow it to fall through the hole in the runway and into the bucket. The added weight of the marble will cause the bucket to fall slowly and the rear end of the rocker beam will rise accordingly with the result that the upward motion of the rackbar will communicate to the horizontal shaft of the crown gear a clock-wise rotation which will swing the post in the same sense of rotation, thereby releasing the trigger lever and allowing it to return to its vertical or stopping position. The bucket will therefore describe a downward spiral movement until it occupies a sufficiently inclined position as to allow the marble to roll out of it. When this occurs, the counter-weight end of the rocker beam will exert a sufficient pressure on the rackbar to slowly push it down thus creating a reverse or counter-clock-wise motion of the rocker beam until the ever rising bucket end strikes against the trigger lever to release a second marble. This motion will be repeated as long as marbles are fed into the trough.

For the purpose of reducing the packing space required by the toy, all the principal parts of the toy are so connected together as to be easily taken apart, by either removing the fulcrum pin of the rocker beam or pressing the feet of the trough supporting legs out of engagement with their respective sleeves.

From the foregoing description, taken in connection with the accompanying drawings, it should be apparent that we have provided a toy of simple construction and positive operation.

It is of course to be understood that the parts may be constructed in various other ways than shown, so therefore we do not wish to be limited in any manner except as set forth in the appended claims.

What we claim is:

1. A toy comprising a base, an elevated marble trough supported on the base, a vertical post on the base in proximity to said trough rotatable about its vertical axis, a transverse beam pivotally carried on the post having a marble receiving bucket at one end thereof, means for normally maintaining the bucket end of the beam in elevated position, said beam being adapted to rock downwardly when a marble is received in the bucket, means actuated through the movement of said beam for feeding marbles into the bucket from said trough one at a time to effect a rocking movement of the beam, cooperating gearing on the post and base for effecting a rotative movement of the post, and means operatively connecting the beam with said gearing for operating the same when the beam is rocked.

2. A toy comprising an elevated marble receiving trough, a vertically pivoted post

- in proximity to the trough, a rocker beam carried by the post on a horizontal pivot, gearing for effecting rotation of the post, said gearing including a fixed curved rack 5 in proximity to the post, a shaft on the post, a pinion on the shaft for engaging the rack, a driving connection between the beam and the shaft for rotating the latter upon a rocking movement of the former, said beam 10 having a bucket at one end and means providing a counter-weight at the other end, delivery means on the trough, and means actuated through the movement of the beam for controlling said delivery means.
- 15 3. A toy comprising an elevated marble receiving trough, means for delivering marbles therefrom, a rocker beam, a vertically pivoted post in which the rocker beam is pivoted carried, a bucket on said beam 20 adapted to receive marbles from said delivery means, a counterweight on the other end of the beam, gearing for rotating the post, means including a rack and pinion for operatively connecting the rocker beam 25 with the post rotating gearing, whereby the post may be rotated when the beam is rocked, and means operated through the movement of the beam for controlling the delivery of marbles from the delivery means 30 to the bucket.
4. In a toy of the character described, a base; a vertical post pivotally mounted at both ends; a rocker beam fulcrumed intermediate the pivots of said post for rocking 35 movement in a vertical plane; a bucket positioned at the forward end and a counter-weight positioned at the rear end of said beam; a horizontally rotating shaft mounted upon and adjacent the lower end of said post; a gear-pinion secured on said shaft and outwardly of said post; a rack-bar having its upper end rockably mounted intermediate the fulcrum and the counterweight 40 of said rocker-beam, and slidably guided for permanent engagement with said pinion; a stationary crown-gear disposed centrally of the lower pivot of said post and secured to said base; a gear secured on the opposite 45 end of said shaft and engaging said crown-gear; an elevated marble holding trough suitably inclined to cause the marbles contained therein to roll by gravity into a runway provided at the forward end of said trough; an aperture provided at the forward end of said runway; a gate secured to a rockably mounted shaft having a downwardly depending finger; a trigger lever outwardly mounted of the runway, the lower 50 arm of said lever operating by the force of gravity to normally hold the gate in a position to arrest the movement of the marbles; the upper arm of said lever being bent outwardly for engagement with the finger of 55 said gate shaft and holding the gate in open position when the lower arm of the trigger lever is struck by the forward end of the rocker beam.
- In testimony whereof they affix their signatures.

JOSEPH WILHELM.
CHARLES A. KAYS.
